UNITED STATES PATENT OFFICE

2,453,555

GAS BLAST CIRCUIT BREAKER

Hans Thommen, Baden, Switzerland, assignor to
 Aktiengesellschaft Brown, Boveri & Cie.,
 Baden, Switzerland

Application March 12, 1945, Serial No. 582,255
 In Switzerland September 11, 1943

Section 1, Public Law 690, August 8, 1946
 Patent expires September 11, 1963

10 Claims. (Cl. 200—148)

1

Gas blast circuit breakers with multiple interruption are known where the contacts are actuated by pressure gas and the arc at the contacts is extinguished by subjecting it to a blast of pressure gas, and where at the same time an impedance (resistance or capacitance) is connected in parallel with the points of interruption, the voltage distribution over the points of interruption being controlled with the aid of this impedance. With this kind of circuit breaker it has been found that when currents of between a low and medium value are interrupted the arc voltage can assume high values, the voltages not being equal at all points of interruption. This results in an unequal voltage distribution over the points of interruption, and this in turn causes difficulties in connection with the extinction of the arc at the various points of interruption which are arranged in series. These disadvantages can be overcome if higher control currents are employed for the impedances. These higher control currents have to be interrupted by a series switch point when the control resistance is disconnected, the isolation of the voltage also being dealt with by this switch. The usual kind of isolating switch is, however, no longer adequate for interrupting these higher control currents.

The present invention thus concerns a gas blast circuit breaker with multiple interruption and voltage control of the compressed-gas operated isolated points of interruption by means of parallel impedances, whereby the disadvantages referred to are overcome according to the invention by the impedances being connected in parallel with the power interrupting points by special switching means. For circuit breakers with a resistance this is particularly advantageous because the resistance can be made so small that the circuit breaker can also be used for over-voltage protection at low currents. A further advantage is that the switching means for the partial resistances do not need to be dimensioned for a continuous current.

Various constructional examples of the invention are illustrated in the accompanying drawings where Figs. 1 and 2 show two different diagrams of connections for the circuit breaker, whilst Figs. 3 to 8 illustrate in diagrammatic form various possible constructional forms of circuit breakers with control resistances.

In all figures a_1 to a_6 indicate the points of interruption of a multiple break gas blast circuit breaker, these points of interruption being arranged in series. For distributing the voltage over the points of interruption control resistances

2

g_1 to g_6 are connected in parallel with the points of interruption. The resistance can consist of a wire or be made of ceramic material. As shown in Fig. 1 each point of interruption can have a part resistance connected in parallel with it, or as shown in Fig. 2 the impedances of several points of interruption can be combined to form a common disconnectable group.

The points of interruption a_1 , a_2 etc. of the circuit breakers shown in Figs. 3 to 7 are equipped with self-closing contacts, one contact of each point being a spring-loaded pin contact which abuts against a nozzle-shaped hollow contact. The contacts of each point of interruption are enclosed in hollow insulators d_1 , d_2 etc. with metallic top and bottom elements. The top and bottom elements support the contacts and are provided with passages for the flow of pressure gas to the contacts and also with outlet openings through which the gas from the contacts can be conducted away. The points of interruption are mounted on a foundation f by means of a hollow supporting insulator e consisting of one or more parts, whereby the foundation f can be used as a compressed gas container and if necessary be mounted on wheels. The control resistances g_1 etc. together with their switching means are arranged in parallel with the points of interruption. These resistances g_1 etc., together with their switching means are located inside hollow insulators i_1 , etc. with metallic bottom and top elements, these insulators being arranged in the form of a column next to the extinguishing chamber insulators of the points of interruption. The extinguishing chambers and the resistances are thus assembled in a similar manner. It is advisable to connect the hollow insulators containing the resistances and their switching means with the extinguishing chambers containing the points of interruption by means of common bottom and cover pieces k_1 etc., which contain the contact elements, as shown for instance in Fig. 3. By this means any number of switch elements can be assembled in column form.

45 The switching means for the resistances can consist of spark gaps with fixed or adjustable electrodes, or of switches with at least one movable switch element. The switching means are preferably subjected to a pressure gas blast and 50 are pneumatically operated. In this case the contacts for the resistance switching means are constructed in the same way as the contacts of the power circuit breaker; that is they are opened by pressure gas and are closed automatically by 55 a spring. The actuating and extinguishing pres-

sure gas for the resistance switches can be taken from the extinguishing chambers containing the points of interruption. The pressure gas for switching the resistances can, however, also be taken from a separate source. In the constructional examples shown in the drawings the gas supply for the points of interruption and the resistance switching means flows through the circuit breaker elements themselves, the switch gases being discharged through the metallic bottom and cover pieces.

With circuit breakers of the kind shown in Fig. 3, when the main valve m is operated pressure gas flows to the extinguishing chambers d_{12} , the points of interruption a_{12} are first opened and the arc at these points is subjected to a gas blast. After a slight delay caused by a throttling action of the gas in the comparatively small passages connecting the extinguishing chambers d_{12} and the hollow insulators t_{12} , switches c_{12} are then opened by the pressure gas and the resistances g_{12} are each disconnected separately. The gas for actuating the contacts and extinguishing the arc thus also serves as an insulating and cooling medium for the resistances.

A series disconnecting switch b as indicated in Fig. 3 (broken lines) is used for isolating the voltage, this switch opening immediately after the points of interruption and the resistance switch have been operated.

Instead of having separate discharge passages for the switch gases as shown at n_1 , n_2 , n_4 in Fig. 3, it is also possible to conduct away the switch gases from the resistance switching means together with those from the interruption points of the circuit breaker, as illustrated in Fig. 4.

The form of the invention shown in Fig. 5 differs from that of Fig. 4 only in so far as spark gaps p_1 to p_3 are used as switching means for the resistances g_1 to g_3 instead of switches, the operation and effect remaining the same and also the application of same. The spark gaps can be provided with pin electrodes or with a pin electrode and a hollow electrode. The spark gaps can be subjected to a transverse or longitudinal gas blast. It is also possible to locate the electrodes of the spark gaps at each side of a nozzle made of insulating material. In Fig. 3 which shows the latter arrangement, the electrodes forming the gap p_1 are located on opposite sides of a nozzle t ; the voltage control impedance is designated g_1 as in the other embodiments previously described.

Fig. 6 shows a gas blast circuit breaker with spark gaps for switching the resistances, where the switch gases from the points of interruption a_1 to a_3 are conducted away over the spark gaps p_1 to p_3 . This arrangement possesses the advantage that the coming into operation of the spark gaps is accelerated by the gases which flow past, this being of importance where high powers are concerned.

Fig. 7 shows a modified form of the invention where the components of the control resistance are fixed one above the other to an insulating tube q which is contained in an insulator r . The spark gaps are located inside tube q . Pressure gas is conveyed to the insulating tube q through pipe s from the arcing chambers d_1 to d_3 . After passing the spark gaps p_1 to p_3 the pressure gas flows between the insulating tube q and insulator r over resistance g_1 to g_3 and out through n_5 to the atmosphere.

Circuit breakers constructed as shown in Figs. 4 to 7 can be used with or without a series dis-

connecting switch, just as is the case with the circuit breaker according to Fig. 3.

I claim:

1. In a circuit breaker, a plurality of normally closed sets of main contacts connected in series circuit relation and operable to open by the application of pressure gas thereto, a plurality of impedances in parallel circuit relation across said sets of main contacts to carry the current upon opening of the main contacts and for controlling the voltage distribution over said main contacts on opening thereof, said impedances having a relatively low magnitude to thereby draw a relatively high order of control current, and pressure gas operated switch means individual to each impedance connecting the same in series circuit relation and adapted to interrupt the flow of current therethrough.
2. A circuit breaker as defined in claim 1 wherein each of said impedances bridges at least two sets of said series connected main contacts when connected by the switch means associated therewith.
3. A circuit breaker as defined in claim 1 wherein the switch means for each impedance is a spark gap, and arcs established across the gaps upon separation of the sets of main contacts are thereafter extinguished by an application of pressure gas thereto.
4. A circuit breaker as defined in claim 1 wherein each of said switch means is constituted by relatively movable and normally closed nozzle and pin contacts separable under the action of pressure gas.
5. In a circuit breaker, a vertical supporting insulator, a plurality of arcing chambers in axial alignment with and superposed upon said supporting insulator, each said arcing chamber comprising a hollow insulator forming the circumferential wall of the chamber and metallic end plates forming the top and bottom walls thereof, passageways through said plates placing said arcing chambers in communication with each other for conducting pressure gas through the several chambers, a set of pressure gas actuated load contacts in each chamber, each contact set including a spring loaded pin contact cooperative with a hollow nozzle contact and separable therefrom under the action of the pressure gas, said pin and nozzle contacts being carried respectively by the metallic end walls of the chambers, an impedance and series connected auxiliary pressure gas operated switch means for each set of load contacts, said impedances being of relatively low magnitude to thereby draw a high order of control current, an insulating member housing each said impedance and switch means, said insulating members being supported between lateral extensions on said end plates that also connect each impedance and switch in parallel with the associated set of load contacts, and means admitting pressure gas to the several insulating members subsequent to the opening of said sets of load contacts to open said auxiliary switch means.
6. A circuit breaker as defined in claim 5 wherein the lateral extensions on said end plates include an internal passageway placing each of said insulating members in communication with the blast chamber associated therewith to receive pressure gas therefrom.
7. A circuit breaker as defined in claim 5 wherein the lateral extensions on said end plates each include an internal passageway placing the nozzle contact of each set of load contacts in

communication with the blast chamber and auxiliary switch means associated therewith to receive pressure gas therefrom.

8. A circuit breaker as defined in claim 5 wherein each of said auxiliary switch means is constituted by an arc gap in which the arc is interrupted by pressure gas to switch the impedance out of circuit with the associated set of load contacts.

9. A circuit breaker as defined in claim 5 wherein each of said auxiliary switch means includes a nozzle contact, said end plates intermediate adjacent sets of load contacts include a pressure gas exhaust outlet, and the lateral extensions of such end plates include a pair of internal passageways, one of said passageways placing the nozzle contact of the switch means in the insulating member supported thereon in communication with the gas outlet therein, and the other passageway placing the blast chamber of which it forms the top end wall in communication with the associated insulating member.

10. A circuit breaker as defined in claim 5

wherein the switch means for each impedance is constituted by an arc gap formed by electrodes arranged on opposite sides of a nozzle of insulating material through which the pressure gas is passed.

HANS THOMMEN.
